In Germany April 30, 1935

12 Claims. (Cl. 9—6)

This invention relates to elastic boats particularly applicable to seaplane floats.

It is a known practice to construct boats with elastic framework and a skin or outer cover made of fabric; in which boats the stem also consists of elastic material, mostly of round or flat steel. This steel must not be too thin otherwise the parts will not possess the requisite strength; on the other hand, even if the steel is of suitable thickness, impacts of any great force against the stem will result in permanent deformation of the latter even when good spring steel is used, because the part struck will be strained beyond its elastic limit so that such a boat cannot be considered to offer sufficient resistance. In order to obtain the desired resistance, it is necessary to distribute the impact over a fairly large section of the material.

The object of the present invention is to attain this desideratum.

According to this invention, in an elastic boat having a rigid keel frame and a resilient framework, there is provided in combination a stem consisting of a helical spring and a tension member both attached at their opposite ends to the keel frame and the gunwale of the resilient framework.

A particular embodiment of the elastic boat according to this invention comprises a rigid keel frame, a framework consisting of resilient ribs, stringers and gunwale, bow and stern stems each consisting of a helical spring and a tension member both attached at their ends to the keel frame and gunwale respectively and a flexible skin covering the said framework.

In a practical construction the stem of my boat consists of a helical spring of ample dimensions let into the heavy keel frame at one end, while the other end is connected at the stem to the gunwale which is made of flat spring steel. Between the two end points of said spring a tensioning member is provided. The object of this is, primarily, to impart the necessary curvature of the spring forming the stem.

At the same time, the tensioning member is required in order by preventing the ends of the spring stretching to their full length and to increase the resistance of the spring, so as to make better use of its elasticity. Moreover, the tensioning imparts a stable form to the ends of the boat, preventing the point of the boat being pulled out, as happens in towing, and also preventing the after stem from yielding outwards under impacts on the forward part of the vessel. As the spiral spring can yield in all directions it is capable of taking up lateral or oblique impacts—coming from forward—such as occur particularly when landing on rock-bound coasts. Excessive mobility is prevented by the floorhead stringers which are also of spring steel and are fixed to the

springs both at stem and stern by means of a sleeve. In order to ensure the utmost possible resiliency of the hull of the boat, it is advisable to avoid riveting as far as possible and only to adopt it at the ends of the ribs at the gunwale, 5 while the floorhead stringers may be arranged in duplicate running in juxtaposition alternately, the ribs being worked under and over the ribs in the manner of adjacent strands of basketwork. The keel frame is very strongly built up of wood 10 and crosses the ribs which are continuously connected with the keel in one piece running from gunwale to gunwale. The spring steel material should be as thin and narrow as possible with a view to elasticity. The thwarts are elastically 15 suspended and are designed to take both tension and compression. The outer skin does not, as in collapsible boats, consist of a combined canvas and rubber skin, but of separate sheets, namely a fabric sheet inside and outside for protection and 20 a middle, very elastic, rubber sheet in between the fabric sheets.

The invention will now be described with reference to the accompanying drawing in which:—

Fig. 1 is a perspective view of an elastic boat 25 constructed in accordance with the invention,

Fig. 2 is a section of a stem along the centre line of the boat,

Fig. 3 a section through one of the thwarts,

Fig. 4 is a similar view to Fig. 3 showing an alternative construction for supporting the thwarts, 30 and

Fig. 5 is a section of a detail.

Referring to the drawing the stem, which may either be at the bow or the stern or both, is provided with a helical spring 1 attached at one end to the gunwale 2 and at the other end to the end of the keel frame 3 as at 4 (Fig. 2). A tensioning arrangement comprising a flexible cable or wire 5 is also attached in a similar manner to 40 the gunwale 2 and the keel frame 3. The nuts fastening this cable or wire to the gunwale and keel frame permit the tension of the wire to be varied.

The framework of the boat is completed by 45 means of ribs 6, which pass under the keel frame 3 as will be later described in greater detail, and by floorhead stringers 7, which are each formed of two strips of spring steel running under and over alternative ribs 6 and disposed adjacent to 50 one another in the manner of adjacent strands in a basketwork. The floorhead stringers 7 which are attached at their ends by means of collars 8 to the helical springs 1 at each stem, carry the floor of the boat (not shown in the drawing) in 55 conjunction with the keel frame 3.

The gunwale 2, the ribs 6 and the floor head stringers 7 are all made of strips of spring steel, which, being both strong and resilient, enables shocks received by the stem to be absorbed. 60

The thwarts 9 are carried at each end by a pair of spring steel supports 10 each attached at their upper and lower ends to a rib 6 near the gunwale 2 and near the floorhead stringers 7. This 5 construction is clearly shown in Fig. 3.

Referring to Fig. 4, an alternative construction for supporting the thwarts 9 is shown, in which the ribs 6 supporting the thwarts 9 are prolonged upwardly and bent over to form a loop 6^a to the 10 inner edge of which the thwarts 9 are attached.

Such arrangements for supporting the thwarts 9 enable rigid thwarts to be used since distortion in shape due to shocks received by the stem or the resilient frame are taken up by the supports 15 10 or 6^a and are not transmitted to the thwarts.

The heavy keel is made up of longitudinal planking 11 laid over the ribs 6, which are supported by a layer of transverse planks 12 and a final layer of longitudinal planking 13, the whole 20 series of planks being bolted together.

Over the framework of the boat, a skin indicated by 14 in Figs. 2-4, said skin consisting of an inner layer 15 and an outer layer 16 of fabric enclosing an elastic layer 17, e. g. rubber, is 25 passed and fixed to the framework by the plate 18 and nut and bolt 19 shown in Fig. 5.

The boat is suitable for use as a lifeboat on ships, because launching it, even in a rough sea, will not cause it much damage. In this case, 30 buoyant chambers would be provided which may be located under the thwarts. It can also be used as pilot's boat and landing boat on rock-bound coasts or for expeditions. It is, however, particularly suitable for use as a float on seaplanes.

35 What I claim as my invention and desire to secure by Letters Patent is:—

1. In an elastic boat having a rigid keel frame and a resilient framework, the combination of a stem consisting of a helical spring and a tension 40 member both attached at their opposite ends to the keel frame and resilient framework.

2. An elastic boat comprising a rigid keel frame, a framework consisting of resilient ribs, stringers and gunwale, at least one stem consisting of 45 a helical spring and a tension member, means for attaching said spring and tension member at their ends to the keel frame and gunwale respectively and a flexible skin covering the said framework.

3. In an elastic boat having a rigid keel frame 50 and a resilient framework, the combination of a stem consisting of a helical spring, a tension member and means for attaching said helical spring and tension member at their opposite ends to the keel frame and to the gunwale of the said 55 resilient framework.

4. An elastic boat comprising a rigid keel frame, a framework consisting of resilient ribs, stringers and gunwale, bow and stern stems each consisting of a helical spring and a tension member, 60 means for attaching both said spring and tension member at their ends to the keel frame and gunwale respectively and a flexible skin covering the said framework.

5. An elastic boat comprising a rigid keel frame, 65 a framework consisting of ribs, stringers and gunwale formed of strips of spring steel, bow and stern stems each consisting of a helical spring and a tension member, means for attaching both said spring and tension member at their ends to the keel frame and gunwale respectively and a flexible skin covering the said framework.

6. In an elastic boat having a rigid keel frame 70 and a resilient framework, the combination of a helical spring and a length of stout flexible cable, means for attaching said spring and cable at their

opposite ends to the keel frame and the gunwale of the said resilient framework, and means for varying the tension of said cable.

7. An elastic boat comprising a rigid keel frame, a framework consisting of resilient ribs and gunwale, bow and stern stems each consisting of a helical spring and a tension member, means for attaching both said spring and tension member at their ends to the keel frame and gunwale respectively, floorhead stringers connecting the bow 10 and stern stem springs which stringers are each formed of two strips of spring steel running under and over alternate ribs and disposed adjacent to one another in the manner of adjacent strands of a basketwork, and a flexible skin covering the 15 said framework.

8. An elastic boat comprising a rigid keel frame, a framework consisting of resilient ribs, stringers and gunwale, bow and stern stems each consisting of a helical spring and a tension member, 20 means for attaching both said spring and tension member at their ends to the keel frame and gunwale respectively, rigid thwarts, and resilient members attached to the ribs and connected to the ends of the thwarts, and a flexible skin covering the 25 said framework.

9. An elastic boat comprising a rigid keel frame, a framework consisting of resilient ribs and gunwale, bow and stern stems each consisting of a helical spring and a tension member, 30 means for attaching both said spring and tension member at their ends to the keel frame and gunwale respectively, rigid thwarts, a strip of spring steel attached to each end of said 35 thwarts, said strip being attached to a rib at one end near the gunwale and at the other end close to the floorhead stringers and a flexible skin covering the said framework.

10. An elastic boat comprising a rigid keel 40 frame, a framework consisting of resilient ribs and gunwale, bow and stern stems each consisting of a helical spring and a tension member, means for attaching both said spring and said 45 tension member at their ends to the keel frame and gunwale respectively, floorhead stringers connecting the bow and stern stem springs, rigid thwarts, an extension of the rib adjacent each end of each thwart being bent downwardly on itself to form a loop to which the thwart is attached, and a flexible skin covering the said 50 framework.

11. An elastic boat comprising a rigid keel frame consisting of a strong keel beam, a layer of transverse planks, a layer of longitudinal planks 55 adjoining the keel and means for rigidly bolting them together, a framework consisting of resilient ribs, stringers and gunwale, bow and stern stems each consisting of a helical spring and a tension member, means for attaching both said 60 spring and tension member at their ends to the keel frame and gunwale respectively and a flexible skin covering the said framework.

12. An elastic boat comprising a rigid keel frame, a framework consisting of resilient ribs, 65 stringers and gunwale, bow and stern stems each consisting of a helical spring and a tension member, means for attaching both said spring and tension member at their ends to the keel frame 70 and gunwale respectively and a flexible skin consisting of an inner and an outer layer of fabric enclosing an elastic layer covering the said framework.
